UNITED STATES PATENT OFFICE

2,043,741

BATH APPARATUS

Joseph Fehn, San Antonio, and Bernhard Schmidt, Lagrange, Tex.

Application September 30, 1935, Serial No. 42,962

4 Claims. (Cl. 4—161)

The present invention relates to new and useful improvements in bath devices and has for one of its important objects to provide, in a single or unitary structure, a combined turkish bath, massage table and shower bath.

Another important object of the invention is to provide a bath apparatus of the aforementioned character embodying a construction and arrangement which is such that the perspiration from the body may be conveniently recovered for the purpose of permitting a diagnosis to be made.

Other objects of the invention are to provide a bath apparatus of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of a bath apparatus or device constructed in accordance with the present invention.

Figure 2 is a view in vertical transverse section, taken substantially on the line 2—2 of Figure 1.

Figure 3 is a vertical transverse sectional view, taken substantially on the line 3—3 of Figure 1.

Referring now to the drawings in detail, it will be seen that the embodiment of the invention which has been illustrated comprises corner posts 1 between which side and end members 2 and 3, respectively, extend. The members 2 and 3, it will be noted, constitute a frame mounted on the lower portions of the posts 1. Extending longitudinally between the upper portions of the pairs of posts 1 are braces 4.

The posts 1 have formed vertically therein opposed grooves or channels 5 for the reception of the vertical marginal portions of slideable plates 6. Further, the posts 1 are substantially hollow to provide chambers 7 in which weights 8 are operable. The weights 8 are connected to the plates 6 by cables or the like 9 which are trained over pulleys 10 mounted in the upper portions of the posts 1. As best seen in Figure 2 of the drawings, the cables 9 are anchored to the plates 6 adjacent the lower ends of said plates, the vertical edges of the plates having grooves therein

which accommodate said cables 9. One of the plates 6 has formed therein a neck receiving opening 11 and the adjacent end member 3 has mounted thereon a head rest 12.

Extending between the plates 6 and mounted thereon is a hood 13 of substantially semi-circular cross section. The hood 13 is of any suitable material, preferably aluminum, and mounted therein is a multiplicity of incandescent lamps 14 for heating purposes. The lower portion of the hood 13 is thickened, as at 15, and provided with longitudinal grooves 16 in which the side members 2 engage when said hood is in lowered position. Handles 17 are provided on the longitudinal sides of the hood 13. The reference numeral 18 designates a shower head which is mounted in the upper portion of the hood 13. The reference numeral 19 (see Figure 1) designates a thermostat which is mounted in the hood 13.

Mounted in the frame provided by the members 2 and 3 is a pan 20 from which water and perspiration drain pipes 21 and 22, respectively, depend. The water drain pipe 21 may extend to any suitable point of discharge. Incandescent lamps 23 are mounted on the side walls of the pan 20 and mounted thereabove are oppositely inclined shields 24. The reference numeral 25 designates a slat table which is removably mounted in the pan 23 above the shields 24. The hood 13 is provided with any desired number of openings which are covered by hinged windows 26 (see Fig. 1), thus permitting access to the interior of said hood to be readily had when desired for any purposes, such as massaging the subject, ascertaining if all is well, etc. Preferably, one window 26 is provided on each side of the hood 13.

It is thought that the manner of using the apparatus will be readily apparent from a consideration of the foregoing. The person using the device reposes on the table 25 with his head engaged on the rest 12. The hood 13 is then lowered and, if a turkish bath is desired, the lamps 14 and 23 are energized. Perspiration from the body passes through the slat table 25 into the pan 20 and flows by gravity through the discharge pipe 22. If desirable or necessary, either or both of the pipes 21 and 22 may be provided with suitable valves. If it is desired to make a diagnosis of the perspiration a receptacle is placed beneath the drain 22 for catching said perspiration. The temperature in the hood 13 is automatically controlled when the apparatus is in use as a turkish bath by the

thermostat 19. If desired, a thermometer may be provided for indicating the temperature in the hood 13. Of course, if a shower bath is desired water from a suitable source of supply to the head 18 is turned "on". The water, after passing over the body, falls through the slat table 25 into the pan 20 and is drained off through the pipe 21. The counterweights 8, of course, materially facilitate lifting the hood 13. 5 With the hood 13 in raised or inoperative position, as shown in Figure 3 of the drawings, a message may be given the subject. The removable table 25 permits access to be readily had to the pan 20 for any purpose, such as for cleaning or for replacing the lamps 23. 10

It is believed that the many advantages of a bath apparatus constructed in accordance with the present invention will be readily understood, and although a preferred embodiment of the device is as illustrated and described, it is to be understood that changes in the details of the construction and in the combination and arrangement of parts may be resorted to which will fall within the scope of the invention as 15 claimed. 25

What is claimed is:—

1. A bath apparatus of the class described comprising hollow supporting posts, a table mounted on the lower portions of said posts, 30 pulleys journaled on the upper portions of the posts, a hood vertically movable above the table, incandescent lamps mounted in said hood, cables connected to the hood and trained over the pulleys, and counterweights mounted on said cables and operable in the posts. 35

2. A bath apparatus of the class described comprising hollow supporting posts, side and end members extending between the lower portions of said posts and constituting a frame, a pan mounted in said frame, drain pipes communicating with said pan, incandescent lamps mounted in the pan, shields mounted in said pan above the lamps, a slatted table removably mounted in the pan above the shields, pulleys 40

journaled on the upper portions of the posts, a hood vertically movable above the table, incandescent lamps mounted in said hood, cables secured to the hood and trained over the pulleys, and counterweights connected to said cables and 5 operable in the posts.

3. A bath apparatus of the class described comprising hollow supporting posts having vertical grooves therein, a table mounted on the lower portions of the posts, pulleys journaled in 10 the upper portions of said posts, vertically slideable end plates engaged in the grooves, a hood extending between the end plates, incandescent lamps mounted in said hood, cables secured, at one end, to the lower portions of the plates and 15 trained over the pulleys, and counterweights secured to the other ends of said cables and operable in the posts.

4. A bath apparatus of the class described comprising hollow supporting posts, said posts 20 having vertical grooves therein, side and end members extending between the lower portions of the posts, said side and end members constituting a frame, a pan mounted in said frame, drain pipes communicating with said pan, in 25 incandescent lamps mounted on the side walls of said pan, oppositely inclined shields mounted in the pan above said lamps, a slat table removably mounted in the pan above said shields, a head rest mounted on one of the end members, vertically movable end plates slidably engaged in the grooves, one of said end plates having a neck receiving opening therein, a hood of substantially semi-circular cross section mounted between said end plates, incandescent lamps 30 mounted in said hood, a shower head mounted in the hood, said hood having grooves in the bottom thereof for the reception of the side members, cables secured, at one end, to the end plates and trained over the pulleys, and counterweights 40 secured to the other ends of said cables and operable in the posts.

JOSEPH FEHN.
BERNHARD SCHMIDT.
